WILLIAM B. LODGE, OF DANBURY, CONNECTICUT, AND HIRAM PLATNER, OF HUDSON, NEW YORK, ASSIGNEES TO THEMSELVES AND F. SHALLER, OF HUDSON, NEW YORK.

Letters Patent No. 66,097, dated June 25, 1867; antedated June 15, 1867.

IMPROVEMENT IN MACHINES FOR SIZING HAT BODIES.

The Schedule referred to in these Letters Patent and making part of the same.

TO ALL WHOM IT MAY CONCERN:

Be it known that we, WILLIAM B. LODGE, of Danbury, in the county of Fairfield, and State of Connecticut, and HIRAM PLATNER, of Hudson, in the county of Columbia, and State of New York, have invented a certain new and useful Improvement in Machinery for Sizing or Planking Hat Bodies, and other articles, whether of fur or wool, or both combined; and we hereby declare that the following is a full, clear, and exact description thereof, reference being had to the accompanying drawings, which form part of this specification, and in which—

Figure 1 represents a side elevation of a machine for sizing hat bodies and other articles constructed according to our improvement.

Figure 2, a similar view, but seen from the opposite side of the machine; and

Figure 3, a vertical longitudinal section of the same.

Like letters refer to like parts in all the figures.

In shrinking fur or wool, or the two combined, as in sizing or planking various articles such as hat bodies, among the mechanism employed for the purpose have been rotating cylinders, vibrating platform, and endless aprons of lags for working said bodies in between them and adjoining shelves or surfaces.

The nature of our present improvement, however, consists in the employment of three or more endless lag-aprons arranged one above the other, and those of each pair made to travel at different velocities relatively to each other, and in opposite directions as regards their contiguous faces; and our invention further consists in so hanging and constructing the one or more of such lag-aprons, or frames which carry them, as to secure to the same a vertical flexibility and adjustability relatively to a lag-apron, having a different velocity and moving in relation thereto, as above specified.

To enable others skilled in the art to which this our improvement relates to make and use our invention, we will now proceed to describe it with reference to the accompanying drawings, in which—

A is the frame of the machine, that may be of rectangular or other suitable shape. At opposite ends of this frame, extending across it, are arranged, one above the other, two or more, say three at each end, drums, B B' B'', hung on horizontal shafts, a and b b'' , that are supported in brackets or blocks C, the centre ones of which at either end may be rigidly secured to the frame A, while the upper and lower ones are vertically adjustable to regulate the distance of the upper and lower drums, and of the endless aprons they carry from the centre drums and their aprons. Each pair of opposite drums have their shafts connected by side-boards, D D', extended to form heads or end covers to the drums which rotate freely within them. These side-boards carry on both sides, that is at opposite ends of the drums, rails or guide-strips e e', which serve to keep the endless belts of lags that pass round the drums from sagging and in their proper course. To the upper and lower of these side-boards D', with their rails e', we give a certain amount of vertical play or flexibility by constructing them in sections d', curvilinearly jointed together as at e, and loosely braced or held together by straps, f, for the purpose of securing an automatic adjustability or flexibility of the upper and lower endless aprons F F', relatively to the centre apron E to make uniform their planking action on the felt-rolls or bodies passing in between them, and which commonly vary in size and consistency. The endless aprons E and F F' passing round their respective drums B B' and B'', are made up of lags bolted or jointed together after the manner of an endless chain, and which may be slightly ribbed, grooved, or corrugated on their outer faces to give a better hold and action on the bodies being planked by them. In addition to the automatic adjustability or flexibility given, as described, to the upper and lower endless aprons F F', the brackets C which carry their drums at opposite ends are made vertically adjustable, as already mentioned, to regulate in a fixed or positive manner the distances of said aprons from the centre apron E, to suit different conditions of work. This adjustability may be effected by raising or lowering, as required, the side-boards D', with their rails and other attachments, including said aprons with their drums and sliding brackets, by means of cams G G' at either end, on opposite sides, secured to cross rock-shafts g g', also acting against suitable stops h h', attached to outside bars connected, as will be hereinafter described, with the side-bars D' of the aprons. The cams G G' may on the one side of the machine, that is each pair for either adjustable apron, be linked together, as shown in fig. 1, by rods i i', pivoted to arms or cranks j j', on the rock-shafts g g', and serving to rock said shafts and their cams by means of levers

H H', pivoted to the frame of the machine, as at $k k'$, and connected with the link-rods or bars $i i'$. The free or outer portions of said levers H H', which latter are separately operative to adjust either the upper or lower apron, or both, as required, may be provided with a projecting catch-pin made to enter any one of a series of holes, $l l'$, in plates I I', secured to the frame of the machine, accordingly as the levers have been moved to the right or left to adjust the aprons up or down to lock said aprons to their adjustment. The cams G G' on the opposite side of the machine, and rocked by the same shafts $g g'$, need not, (as illustrated in fig. 2,) be of necessity linked together. The outside bars J J' to the side-boards D' on both sides of the machine, are, (say the upper ones of the bars J' of the lower apron, and under ones of the bars J of the upper apron,) divided and bolted in sections corresponding with the sectional construction of the side-boards D' to the latter, while the lower ones of the bars J' of the lower apron, and upper ones of the bars J of the upper apron are left free and independent of said side-boards and not made in sections, but connected with their sectional adjacent bars by regulating or tightening up screw-bolts K, and springs L fitting round stems projecting from said bars, so that said upper and lower aprons have not only a flexibility given them by reason of the sectional construction of their side-boards D', and up or down adjustment by the levers H H', but have their general flexibility or rigidity capable of being regulated at pleasure accordingly as the nuts of the screw-bolts K are turned to compress or relieve the springs L. This gives great adaptability to the machine, and enables it to conform to various kinds and sizes of work, and insures unfailing action. Instead of springs to effect this general flexibility, weights, or a system of weights and levers may be used. Supposing motion to be communicated to one of the central drums B by a pulley, M, on its shaft, so as to give a travelling movement to the middle apron E in the direction shown by the arrows in fig. 3, then the boards N and O will represent first and second feed-boards for passing the bodies to undergo planking through the machine and returning them, which operation may be repeated as often as necessary, after first and from time to time immersing said bodies in the battery and folding them in different directions in their wrapper, as usual in sizing. Where a quick travel through the machine is required to be given said bodies or roll into which they are formed, then the upper and lower aprons F F' may be stationary or have no positive driving action communicated to them; but in such case the roll, it will be perceived, can make but few turns in its passage through a comparatively short machine, and consequently the hat or other bodies are but little "worked," which in many cases would render it necessary to pass and repass them repeatedly for a very lengthened period through the machine. To obviate this, and to secure the bodies being better worked, we impart to either or both of the aprons F F' a positive motion by gearing their drums at one end with the driving-drum of the central apron E, in such manner as that said drums will all rotate, but the upper and lower ones at a reduced velocity, say one-half more or less to the central one. This will cause the upper and lower aprons, or either, to act in a reverse direction on the roll passing in between them and the central and quicker moving apron, so as to considerably retard its passage through the machine and cause it to be rotated much more frequently during said passage, thereby giving more "work" to the hat-bodies. The means for effecting this may consist of a spur-wheel, P, on the central apron-drum shaft made to gear, through intermediate wheels Q R, say of like diameter to P, with larger wheels S T on the shafts of the upper and lower apron-drums. The sizes and arrangements, however, of these wheels may be varied so as to give any required differential velocity to the aprons. But as in some cases, or at certain times in the progress of the work, it may not be necessary thus to operate on the hat bodies or rolls, we make the intermediate gear Q R, either one or both, to unship from gear with the wheels S T on the upper and lower drum-shafts by supporting the shafts of said intermediate gear in hangers or levers U U', arranged loose on the central drum-shaft, and serving, when released from a perforated and adjustable spring-holder, V, or other suitable device, to throw the wheels Q R out of gear with the wheels S T, or either of them, as shown by red lines in fig. 2. Or one of said intermediate wheels, say R, may be thus unshipped from gear with the wheel T on the lower drum-shaft, while the other intermediate wheel Q may be thrown and held in gear with the wheel S on the upper drum-shaft by hitching the spring-holder on to the lever U, so that the hat bodies or roll in passing underneath the upper apron or over the middle one will be largely worked or frequently rotated, but on returning it under the middle apron and on or over the under one it will be comparatively seldom rotated and rapidly passed on. This facility for diversifying the working character of the machine will be found very serviceable in sizing or planking operations generally, and coupled with the adjustability and flexibility of the upper and lower aprons, or either, if the two or both be used, the machine will be found much more perfect than those heretofore employed. The intermediate wheels Q R may have their bearings or shafts secured in slots s in the hangers or levers U U', so that said wheels may, if desired, be also slid out of gear with the wheel P on the central drum-shaft, or another wheel of different diameter may be substituted for P, and the same levers by their slots s be made to accommodate such change, and thus vary the relative velocity of the upper and lower aprons with regard to the central one.

What we claim as our invention, and desire to secure by Letters Patent, is—

1. In hat-planking machines the arrangement of three or more endless belts or aprons of lags made to travel with their contiguous faces or surfaces in opposite directions, at different velocities relatively to each contiguous one, substantially as specified.
2. The combination, with an endless belt or apron, E, of lags, having a fixed or positive motion of two or more endless lag-belts or aprons F and F', arranged as specified, and so geared to operate in connection with the belt E, as that they, F and F', can, during the progress of the work, be made at pleasure to travel with their surfaces adjacent to E, in a reverse direction at a reduced velocity relatively thereto, or be left free to act independently of it, substantially as described.
3. The combination of the lag-belts E, and F or F', drums B and B¹, or B², at the one end of the machine,

wheel P, levers U or U', and wheels Q and S, or R and T, for operation, essentially as and for the purpose or purposes herein specified.

4. Constructing the side-boards D', with their rails d', in sections, and holding or uniting them by springs or weights, and screw-bolts, to give the lag-apron F or F' a vertically flexible character, substantially as herein set forth.

5. The combination with a stationary arranged endless lag-belt or apron E of one or more lag-aprons F or F', arranged to travel at a reduced velocity and relatively to the belt E, as specified, and made vertically adjustable in relation thereto by means of lifting-cams G G', or other suitable devices, essentially as specified.

6. The combination with an endless lag-belt or apron, E, having inflexible rails or guides, e, of an endless lag-belt, F or F', with its rails or guides e' made in sections and flexible, said aprons E and F or F', being arranged and operating relatively to each other substantially as described.
